UNITED STATES PATENT OFFICE.

FRANCIS M. UNDERHILL, OF NEW YORK, N. Y., ASSIGNOR TO WHITALL,
TATUM & CO., OF SAME PLACE.

DESIGN FOR A JAR.

SPECIFICATION forming part of Design No. 21,612, dated June 7, 1892.

Application filed May 6, 1892. Serial No. 432,085. Term of patent 14 years.

To all whom it may concern:

Be it known that I, FRANCIS M. UNDERHILL, a citizen of the United States, residing in the city, county, and State of New York, have invented and produced a new and original Design for an Ointment-Pot, of which the following is a specification, reference being had to the accompanying drawings, forming part hereof, wherein—

10 Figure 1 is a side view of my new design for an ointment-pot. Fig. 2 is a vertical central section of the same.

This invention relates to a new configuration of jar or ointment-pot; and it consists, 15 mainly, in providing the cylindrical body of the pot with projecting circumferential ribs at the ends of the cylinder and in rounding the body of the bottle where it extends beyond

said ribs, substantially as hereinafter described.

In the drawings, the letter *a* represents the cylindrical body of my new design for a jar or pot. At the upper end this cylindrical body meets a projecting rib *b*, and at the lower end it meets a projecting rib *d*. Below the rib *d* 25 the side of the vessel slopes at *e* from a point nearly in line with the wall of cylinder *a* toward a contracted bottom *f*. Above the rib *b* the pot also slopes inwardly, as at *g*.

What I claim is—

The design for a jar or pot, substantially as shown.

FRANCIS M. UNDERHILL.
